Patented Apr. 13, 1920.

UNITED STATES PATENT OFFICE.

ANGUS H. GIBSON, OF SALT LAKE CITY, UTAH.

CENTRIFUGAL MACHINE.

1,336,779.

Specification of Letters Patent.

Patented Apr. 13, 1920.

Application filed April 21, 1915, Serial No. 32,793. Renewed June 25, 1919. Serial No. 306,715.

To all whom it may concern:

Be it known that I, ANGUS H. GIBSON, citizen of the United States, and resident of Salt Lake City, Utah, have invented 5 certain new and useful Improvements in Centrifugal Machines, of which the following is a specification.

This invention relates to centrifugal machines of the type commonly used in sugar 10 refineries and is intended to provide a convenient and efficient construction by which the sugar accumulated on the interior of the centrifugal basket may be efficiently and quickly discharged by the automatic operation 15 of the machine after each charge of sugar has been purified by centrifugal action and washed in the usual manner.

To this end the invention comprises the combination with the rotary basket and its 20 shaft of a vertically movable bottom connected with actuating mechanism by which the bottom is lowered automatically by the braking or slowing down of the machine.

In the accompanying drawings I have 25 illustrated a simple and convenient form of mechanism for effecting the discharge of the sugar upon the principle referred to.

Figure 1 is a side elevation in vertical 30 section of the well-known type of sugar centrifugal machine equipped with my invention.

Fig. 2 is a plan view partly broken away to show underlying portions.

Fig. 3 is an enlarged detail view of the 35 lower portion of the basket in vertical section.

The invention herein is shown as applied to a well-known type of sugar centrifugal machine comprising a gyratory shaft a rotatably suspended in an oscillatory head a' , which is mounted in the fixed hanger a'' , the shaft being driven by any suitable means, as by a driving pulley a^2 inside of 40 which is shown a well-known type of expansible brake a^3 .

The centrifugal basket comprises the 45 perforated cylindrical wall b properly reinforced and secured at its lower end to a strong ring b^2 which is preferably cast integral with the supporting spider b^3 which is provided with concentrically arranged upwardly extending supporting arms b^4 between which are left large peripheral openings for the escape of the sugar outward 50 when it is discharged from the basket. The spider has a central hub b^5 by which it is

rigidly secured to the lower end of the shaft a .

The basket has the usual top rim b^6 but its lower end is open and is normally closed 60 during the operation of the machine by a vertically movable circular plate or bottom c provided with a depending rabbeted flange c' which makes a tight or close joint with the lower edge portion of the basket 65 when in raised or closed position. The movable bottom c is connected by means of a cone or spider c^3 with a supporting and actuating sleeve c^2 which surrounds the basket shaft a , said sleeve c^2 being provided 70 with an external screw-thread.

The raising and lowering member herein shown comprises a sleeve d provided with a weighted or momentum wheel d' and mounted upon a thrust or bearing collar d^2 75 secured to the shaft so as to permit rotative movement of the sleeve d in relation to the basket shaft. An anti-friction thrust bearing, as shown at d^3 , may be used to diminish friction. The sleeve d is internally 80 screw-threaded, as shown at d^4 , to engage the exterior thread on the bottom supporting sleeve c^2 .

These engaging screw-threads of the actuating member d and the supporting 85 sleeve c^2 are so formed that in starting the machine in operation any tendency on the part of member d , d' to lag behind the shaft serves to raise the sleeve c^2 and the movable bottom c and so that when the brake is 90 applied to the shaft a , the momentum of the bottom actuating member d causes said member to continue its rotation at a higher speed than the rotation of the basket shaft when slowed down by the brake and therefore depresses or lowers the movable bottom c to its lowermost position below the 95 peripheral openings in the spider b^3 , b^4 .

After the basket has been emptied while the machine is being brought up to normal 100 speed a brake e mounted on a bracket e' above the curb f is pushed into braking engagement with the wheel d' so as to retard the sleeve d in relation to the basket shaft and thereby raise the bottom c into its 105 uppermost or closing position. This brake is normally kept out of engagement with the wheel d' by a spring e^2 .

In order to assist in guiding the movable bottom, I provide inwardly projecting ribs 110 b^8 on the spider arms b^4 , and on the under side of the bottom c at its periphery, I se.

secure a series of brackets c^5 each carrying a pair of slightly spaced anti-friction rollers c^6 arranged to engage the opposite faces of the guide rib b^8 . The conical connecting spider c^3 may also be provided with a downwardly extending tubular collar c^{10} engaging the upwardly extending cylindrical portion b^{10} of the spider hub to serve as centralizing guiding means to prevent the sleeve c^2 from binding upon the basket shaft. The antifriction rollers serve to prevent any binding engagement between the movable bottom and the basket spider while at the same time securing their rotation in perfect unison.

To secure a tight joint between the bottom c and the lower edge of the basket I prefer to form the lower edge of the basket with a tapered or connecting edge, as shown at b^{12} , to shear off any sugar that may collect in the rabbeted edge of the movable bottom. Since the pressure of the syrup and the sugar against the wall of the basket during the centrifugal separation is very great, I provide for draining the joint between the basket and the movable bottom by scoring an annular groove b^{13} on the inside of the basket near its lower edge and providing a series of perforations running from this groove out through the ring b^2 , as shown at b^{14} .

To assist in breaking down the walled-up sugar when the bottom is lowered for discharging purposes, I provide a series of hooked arms or sugar-engaging members g which are pivotally connected with brackets g' secured to the bottom c . The hooks or heads g^2 at the upper end are embedded in the sugar wall and act as a sort of hoe to pull down the sugar when the bottom is lowered. The sugar-engaging members will remain normally against the peripheral wall of the basket, owing to centrifugal force. They are prevented from falling inward by angularly projecting feet g^3 .

The basket curb f is provided with an annular trough f' in position to catch the extracted syrup which flows down outside of the flange ring b^2 . The inner wall of this trough is also positioned to serve as a deflector to throw sugar downward into a hopper or receptacle beneath the curb.

It will be seen that the discharge of the sugar is effected automatically when stopping the machine in the usual way without extra effort or labor on the part of the attendant, and that the discharge is effected almost instantaneously by centrifugal action while there is nothing to interfere either with the inspection of the interior of the basket or with the washing operation before the sugar is discharged.

What I claim is:

1. In a centrifugal machine the combination with a rotary shaft and a centrifugal

basket secured thereto, a vertically movable bottom for sustaining the solid matter as it accumulates in the basket, means for raising and lowering said movable bottom to close and to open respectively the lower end 70 of the basket, said means being actuated automatically by the slowing down of the basket, substantially as described.

2. In a centrifugal machine the suspended rotary shaft, a centrifugal basket secured to the lower end thereof, a vertically movable bottom arranged to normally close the lower end of the basket to support the solid content, a vertically movable sleeve surrounding the shaft and connected 80 with the movable bottom, and means for engaging said sleeve and actuated by the momentum of rotation to lower the sleeve and the bottom when the rotation of the shaft is retarded, substantially as described.

3. The combination with a suspended gyroratory shaft, a centrifugal basket secured to the lower end thereof, a vertically movable circular bottom plate arranged to close 90 the lower end of the basket during the normal operation of the machine, a supporting member extending upwardly around the shaft and connected with said bottom, and an actuating member rotatably mounted on the shaft and having operative connection with said supporting member to lower said supporting member when rotating at a faster speed than the rotation of the basket shaft, substantially as described. 100

4. In a centrifugal machine the combination of the suspended rotary shaft, a centrifugal basket secured to the lower end thereof, a vertically movable bottom arranged to close the lower end of the basket 105 during the normal operation of the machine, a screw-threaded slide sleeve mounted on the shaft and connected with the bottom, a co-operating actuating member loosely mounted on the shaft so as to be 110 rotatable at a different rate of speed in order to move said bottom vertically, substantially as described.

5. The combination with a rotary centrifugal basket and its central driving shaft, 115 a vertically movable bottom arranged to close the open lower end of said basket, an actuating member rotatably mounted on said shaft, means for operatively connecting the bottom with said actuating member, means for retarding the basket shaft, and means for retarding said actuating member whereby through a differential rotation of the actuating member in relation to said shaft the bottom may be opened or 125 closed, substantially as described.

6. The combination with a basket shaft and its basket suspended from an over-head bearing, a weighted sleeve rotatably mounted upon said shaft, a vertically movable 130

- bottom arranged when raised to close the lower end of the basket, means for operatively connecting said rotatable sleeve with the movable bottom, said means acting to 5 lower the bottom when the sleeve is rotating faster than the basket shaft and to raise the bottom when said sleeve rotates slower than the basket shaft, substantially as described.
- 10 7. The combination of a rotary shaft suspended from an overhead support, a centrifugal basket secured to its lower end, a vertically movable bottom arranged to normally close the lower end of the basket, 15 means mounted on the shaft between the basket and the overhead support to raise and lower said bottom automatically by the differential rotation of the basket and said raising and lowering means, and upwardly 20 extended members connected with said bottom to engage and pull down the wall of sugar when the bottom is lowered, substantially as described.
8. The combination of the centrifugal 25 basket rotatably suspended from an overhead support, a vertically movable bottom arranged to normally close the lower end of the basket, upwardly extending arms pivotally connected with the bottom and 30 having their upper ends normally resting against the peripheral wall of the basket, and automatically operated means mounted on and normally rotating with the centrif-
- ugal basket for lowering the bottom to permit the discharge of the solid content when 35 the rotation of the basket is retarded, substantially as described.
9. The combination with the central driving shaft of a basket-supporting spider whose arms are extended upwardly at their 40 outer ends, a peripheral basket screen mounted upon the upper ends of said arms and provided near its lower edge with an annular groove having outlet perforations extending to the outside of the basket, a 45 vertically movable bottom having a flanged periphery constructed to fit into the lower edge of the basket beyond said annular groove, and means for raising and lowering said bottom to permit the discharge of 50 the solid content, substantially as described.
10. A self-discharging centrifugal machine embracing in its construction a central driving and supporting shaft, a centrifugal basket structure comprising a peripheral member, and a coöperating bottom member, both supported by said shaft, one of said members being vertically movable in relation to the other, to separate them for discharging purposes, and means automatically operated by the rotation of the machine, to separate the two members, substantially as described.

In witness whereof, I have subscribed the above specification.

ANGUS H. GIBSON.
